UNITED STATES PATENT OFFICE.

PHILIP W. MOORE, OF EVANSTON, ILLINOIS, ASSIGNOR TO THE P & M COMPANY, OF CHICAGO, ILLINOIS, A CORPORATION OF ILLINOIS.

RAIL-ANCHOR.

1,254,258.

Specification of Letters Patent. Patented Jan. 22, 1918.

Application filed May 21, 1917. Serial No. 169,934.

To all whom it may concern:

Be it known that I, PHILIP W. MOORE, a citizen of the United States, residing at Evanston, in the county of Cook and State of Illinois, have invented certain new and useful Improvements in Rail-Anchors, of which the following is a specification.

My invention relates to devices for the purpose of preventing the longitudinal movement or creeping of railroad rails, and more particularly to an anti-creeping device or rail anchor of the general type of the anchor patented to D. F. and D. L. Vaughan in United States Letters Patent No. 1,021,387, issued March 26, 1912, in which spring action is relied upon to maintain a firm hold of the device on the rail.

The principal object of this invention is to provide an anchor, of the spring type, which will grip with equal tenacity rails, the base flanges of which differ somewhat in size or contour. Rails even of the same weight and made presumably in conformity with the same standard will be found not infrequently to differ to a certain extent, in their base flange dimensions due, for example, to incorrect rolling, or it may be to corrosion of the base of the rail after the rail has been subjected to the weather for some time. In an anchor of the spring type any deviation from the standard contour involving a narrowing or thinning of the base flanges results necessarily in lessening the effective grip of the device on the rail provided there is no provision in the anchor itself for adapting it to rail bases of the lesser dimensions. My invention provides a rail anchor so constructed as to permit an initial adjustment or application of the device to a rail which may be made in accordance with the size and contour of the rail base so that any ordinary variation from the standard contour does not impair the effectiveness of the device in the performance of its intended function.

While I have shown a rail anchor which, except for the improvements constituting this invention, closely resembles, in the form and construction of its parts, the rail anchor of the patent above referred to, it will be apparent that the principles of the present invention might be embodied in the construction of devices of different type from that chosen and here shown for the purpose of illustrating my present invention in a typical and preferred embodiment.

In the drawings,

Figure 1 is a plan view of a rail anchor constructed in accordance with my invention shown as applied to a rail.

Fig. 2 is a side view of the device, showing the rail in section, looking in the direction toward the tie against which the rail bears.

Fig. 3 is an end view of the anchor showing the spring member in the position of interlocked engagement with the other member of the anchor which it takes on rails of maximum size.

Figs. 4 and 5 are similar views to illustrate adjustments of the spring member for rails having base flanges smaller in their dimensions.

Fig. 6 is a view, in perspective, of the shoe or rigid element of the anchor, and

Fig. 7 is an end view of the device to illustrate the manner in which the engagement between the spring member and shoe is brought about.

Like characters of reference designate like parts in the several figures of the drawings.

In the drawings the rail is indicated at 10 and the tie at 11. The arrow (Fig. 1) indicates the creeping tendency which the anchor is designed to check.

The anchor consists of a shoe or rigid member 12, which is preferably a malleable casting, and a spring bar 13 preferably made of steel. The casting 12 is formed to provide a jaw 14 which engages one edge of the base flange 15 of the rail, and a foot or tie abutting plate 16 adapted to bear against the side face of tie 11.

The spring member 13 is formed with a hook or jaw 17 adapted to engage the base flange of the rail at a point opposite shoe 12, the upper portion of the jaw being bent so as to provide a diagonally disposed lip 18 which bears upon the upper surface of the rail base. The other end of the spring member 13 is formed with an enlargement 19. The portion of the spring member extending under the base of the rail is preferably, though not necessarily, given a slight twist so the normal position of the enlargement 19 will be oblique to the plane of the jaw 17. The shoe is formed with a recess 20 adapted to receive the enlargement 19 on the spring member. The web 21, on one side of the recess 20, is formed with notches providing a series of stepped seats 22, 23, 24 for the

upper edge of the enlargement 19. The web 25 on the other side of recess 20 is provided with a lug 26 formed with notches providing a series of stepped seats 22^a, 23^a, 24^a for the lower edge of the enlargement 19 of the spring member. The web 25 is preferably, but not necessarily, formed above lug 26 with a stop lug 27.

The device is applied to the rail in the manner shown in Fig. 7. The shoe 12 is driven upon one edge of the rail base. The hook 17 of the spring member is engaged with the opposite edge of the rail base, the enlargement 19 lying in the recess 26 in the shoe. By means of a claw bar or wrench 28 applied to the enlargement 19, the spring member is twisted and raised so that it may be seated against one of the three pairs of seats 22, 22^a, 23, 23^a or 24, 24^a (Figs. 3, 4 and 5). For a rail having a base of the maximum dimensions the spring member will be engaged with the seats 22, 22^a. For rails having smaller rail bases the spring member may be made to engage either with seats 23, 23^a or seats 24, 24^a. When the spring member 13 is in either of the above positions, the spring action of the member, in tending to assume the normal position from which it was sprung by a torsional or twisting action when being applied, is exerting a forward and downward pressure on the diagonally disposed lip 18 against the rail base. A reverse or rearward pressure upon the enlargement 19 is exerted against the notched seats 22, 23 or 24, as the case may be, thus causing the jaw 17 to firmly grip the rail base.

By the arrangement just described the tenacity with which the anchor engages the rail will not be affected even if the base of the rail be worn through corrosion or is smaller than the standard contour due to incorrect rolling. The difference in the size of the rail bases will be compensated by the greater distortion produced when the spring member is engaged with seats 23, 23^a or seats 24, 24^a. In any case, the torsional strain of the spring member produces a stress by which the tie-abutting member or shoe is firmly held to the rail. By means of the different interlocked engagements between the spring member and the shoe this stress may be maintained at approximately the maximum, with reference to the capacity of the spring member to resist breaking, even though, as frequently happens, the rail base may be smaller than normal.

I claim:

1. A rail anchor comprising members embracing the base of the rail, one being a spring, which are capable of different interlocked engagements with each other to accommodate the anchor to rail bases of differing contour.

2. A rail anchor comprising a shoe and a spring member which together embrace the

base of the rail and which are capable of different interlocked engagements with each other to accommodate the anchor to rail bases of differing contour.

3. A rail anchor comprising a shoe and a torsion spring member which together embrace the base of the rail and which are capable of different interlocked engagements with each other to accommodate the anchor to rail bases of differing contour. 75

4. A rail anchor comprising a shoe engaging the rail base on one side thereof and a spring bar extending around said shoe and the opposite edge of the rail base, and adapted to have different interlocking engagements with the shoe to accommodate the anchor to rail bases of differing contour. 80

5. A rail anchor comprising a shoe engaging the rail base on one side thereof and a spring bar capable of torsional strain extending around said shoe and the opposite edge of the rail base, and adapted to have different interlocking engagements with the shoe, which subjects the spring to torsional strain, to accommodate the anchor to rail 90 bases of differing contour.

6. A rail anchor comprising a shoe engaging the rail base on one side thereof and a spring bar extending around said shoe and the opposite edge of the rail base, and means 95 on said bar and shoe whereby said elements may have different interlocking engagements subjecting the spring bar to strain.

7. A rail anchor comprising a shoe engaging the rail base on one side thereof and a spring bar extending around said shoe and the opposite edge of the rail base, and means 100 on said bar and shoe whereby said elements may have different interlocking engagements subjecting the spring bar to torsional 105 strain.

8. A rail anchor comprising a shoe engaging the rail base on one side thereof and a spring bar extending around said shoe and the opposite edge of the rail base, and means 110 on said bar and shoe whereby said elements may have different interlocking engagements subjecting the spring bar to strains of different degrees.

9. A rail anchor comprising a shoe engaging the rail base on one side thereof and a spring bar extending around said shoe and the opposite edge of the rail base, and means 115 on said bar and shoe whereby said elements may have different interlocking engagements subjecting the spring bar to torsional strains of different degrees.

10. A rail anchor comprising members embracing the base of the rail, one being a spring, which are capable of different engagements with each other, each of which produces distortion of said spring member. 125

11. A rail anchor comprising members embracing the base of the rail, one being a spring, which are capable of different en- 130

gagements with each other, each of which produces a torsional strain of the spring member.

12. A rail anchor comprising members embracing the base of the rail, one being a spring, which are capable of different engagements with each other which produce strains of different degrees in said spring member.

10 13. A rail anchor comprising members embracing the base of the rail, one being a spring, which are capable of different engagements with each other, which produce torsional strains of different degrees in said 15 spring member.

14. A rail anchor comprising a shoe and a spring which together embrace the base of the rail and are capable of different engagements with each other to produce distortion 20 of the spring member.

15. A rail anchor comprising a shoe and a spring which together embrace the base of the rail and are capable of different engagements with each other to produce distortion 25 of the spring member in different degrees.

16. A rail anchor comprising a shoe and a spring which together embrace the base of the rail and are capable of different engagements with each other to produce torsional 30 strain of the spring member.

17. A rail anchor comprising a shoe and a spring which together embrace the base of the rail and are capable of different engagements with each other to produce torsional 35 strain of the spring member in different degrees.

18. A rail anchor comprising a shoe and a spring member which together embrace the base of the rail, said shoe being formed with 40 a plurality of pairs of seats adapted to be engaged by the spring member with an engagement which subjects said member to strain.

19. A rail anchor comprising a shoe and a 45 spring member which together embrace the base of the rail, said shoe being formed with a plurality of pairs of seats adapted to be engaged by the spring member with an engagement which subjects said member to 50 torsional strain.

20. A rail anchor comprising a shoe and a flat spring bar which together embrace the base of the rail, said shoe being formed with a plurality of pairs of stepped notches adapted 55 to be engaged by the edges of the spring bar with an engagement which subjects said bar to strain.

21. A rail anchor comprising a shoe and a flat spring bar which together embrace the 60 base of the rail, said shoe being formed with a plurality of pairs of stepped notches

adapted to be engaged by the edges of the spring bar with an engagement which subjects said bar to strain which varies in accordance with the particular pair of notches 65 engaged by said spring member.

22. A rail anchor comprising a shoe having a jaw adapted to fit over one edge of the base flange of a rail, and a flat spring bar having a hook adapted to engage the 70 opposite edge of the rail base and provided at its opposite end with an enlargement, said shoe member being formed with two sets of stepped notches adapted to be engaged by the enlargement of the spring member so as 75 to subject said spring member to torsional strain.

23. A rail anchor comprising a shoe and a spring member which together embrace the base of the rail, said shoe being formed with 80 a plurality of seats adapted to be engaged by the spring member with an engagement which subjects said member to strain.

24. A rail anchor comprising a shoe having a jaw adapted to fit over one edge of 85 the base flange of a rail, and a flat spring bar having a diagonally disposed hook adapted to engage the opposite edge of the rail base and provided at its opposite end with an enlargement, said shoe member being formed 90 with stepped notches adapted to be engaged by the enlargement of the spring member so as to subject said spring member to torsional strain.

25. A rail anchor comprising a shoe having a jaw adapted to fit over the edge of the base flange of a rail, and a flat spring bar having a jaw adapted to engage the opposite edge of the rail base and provided at its opposite ends with an enlargement disposed 100 obliquely with respect to the plane of said last mentioned jaw, said shoe member being formed with stepped notches adapted to be engaged by the enlargement of the spring member so as to subject said spring member 105 to torsional strain.

26. A rail anchor comprising a shoe having a jaw adapted to fit over one edge of the base flange of a rail, a spring bar having a jaw adapted to engage the opposite 110 edge of the rail base and provided at its opposite end with an enlargement, the portion of the spring member intervening between the said last mentioned jaw and said enlargement being twisted so that the jaw 115 and enlargement will have a normal set in opposite directions, and said shoe member being formed with stepped notches adapted to be engaged by the enlargement of the spring member so as to subject said spring 120 member to torsional strain.

PHILIP W. MOORE.
